(57) CLAIM

The ornamental design for a pistachio nut opener, as shown and described.

DESCRIPTION

FIG. 1 shows a perspective view of my design for a pistachio nut opener;

FIG. 2 shows a top view thereof, with the bottom view being identical;

FIG. 3 shows a side view thereof, with the opposite side view being a mirror image thereof; and,

FIG. 4 shows a front view thereof.

The areas in dotted lines show environmental structure only and form no part of the invention.

UNITED STATES PATENT AND TRADEMARK OFFICE
CERTIFICATE OF CORRECTION

PATENT NO. : Des. 545,643 S
APPLICATION NO. : 29/233974
DATED : July 3, 2007
INVENTOR(S) : Roger

It is certified that error appears in the above-identified patent and that said Letters Patent is hereby corrected as shown below:

In particular, on the title page, Item [76], change "21 Break La.," to correctly read:
--21 Brook La.,--.

Signed and Sealed this

Eleventh Day of September, 2007

A handwritten signature in black ink, appearing to read "Jon W. Dudas". The signature is written in a cursive style with a large, stylized 'J' at the beginning.

JON W. DUDAS
Director of the United States Patent and Trademark Office
